Patented July 29, 1975

236,126

BATTERY CABLE TERMINAL

James Demetreon, 5704 Hillside Drive,
Kansas City, Mo. 64151

Filed Dec. 5, 1973, Ser. No. 421,934

Term of patent 14 years

Int. Cl. D13—03

U.S. Cl. D26—1 E

Fig. 1.

Fig. 2.

Fig. 3.

Fig. 4.

Fig. 5.

Fig. 6.

Fig. 7.

FIG. 1 is a perspective view of a battery cable terminal showing my new design;

FIG. 2 is a top plan view of the terminal shown in FIG. 1;

FIG. 3 is a bottom plan view of the terminal shown in FIG. 2;

FIG. 4 is a front elevational view of the terminal shown in FIG. 2;

FIG. 5 is a rear elevational view of the cable terminal shown in FIG. 2;

FIG. 6 is a left end elevational view of the cable terminal shown in FIG. 2; and

FIG. 7 is a right end elevational view of the terminal shown in FIG. 2.

I claim:

The ornamental design for a battery cable terminal, as shown and described.
